SWIVEL

William A. H. Wells, Providence, R. I.

Application November 10, 1937, Serial No. 173,777

4 Claims. (Cl. 24—240)

This invention relates to a swivel; and has for one of its objects the provision of a construction which will be much simpler to form than the constructions which are usually offered on the market.

Another object of the invention is the provision of a swivel which will be formed of fewer parts and yet be a stronger construction whereby less assembly operations are necessary and the liability of the separation of the parts be minimized.

Another object of the invention is the formation of a swivel which will be so constructed that the shot used in finishing the swivel will not accumulate in the body thereof to hamper the action of the parts and make removal of the shot necessary.

Another object of the invention is the formation of a guide and retaining means for a wire spring in the swivel.

With these and other objects in view, the invention consists of certain novel features of construction, as will be more fully described, and particularly pointed out in the appended claims.

25 In the accompanying drawing:

Fig. 1 is a perspective view of the finished device:

Fig. 2 is a central longitudinal sectional view of the parts shown in Fig. 1 taken substantially 30 in the plane of the ring there shown with the tongue in closed position;

Fig. 3 is a view similar to Fig. 2 showing the tongue in open position;

Fig. 4 is a sectional view of the hollow body 35 or tube portion of the swivel alone;

Fig. 5 is an end view of the body shown in Fig. 4;

Fig. 6 is a sectional view of the blank which is bent up to provide both bow and tongue;

40 Fig. 7 shows the blank bent up in the bow and tongue form;

Fig. 8 is a top plan view of the structure shown in Fig. 7.

In the formation of swivels of this general 45 character it is usual to provide an arm at the end of the bow which is partly severed just prior to bending and a tube is soldered in the severed portion at the gap of the partly severed portion, which tube receives a pivot pin which is an individual member riveted into the tubular body. A spring engages this arm while the other end of the bow is soldered to the body. This structure requires many labor and assembly operations, some of which are required to be performed 50 by highly skilled workmen with the correspond-

ing expense of construction, all of which may be much lessened by the structure which I provide wherein a part of the end wall of the body is utilized as the pivot bar and the end of the bow which forms the tongue is merely bent around this bar to provide its pivotal mounting; and I have extended the other end of the bow which is soldered to the body toward this pivot so that it not only forms the function of preventing the entrance of shot into the body but also serves 10 by reason of a slot herein as an effective guide and positioning structure for the resilient spring; and the following is a more detailed description of the present embodiment of this invention, illustrating the preferred means by which these advantageous results may be accomplished:

With reference to the drawing, 10 designates a hollow generally tubular formation of body with somewhat conical side walls 11 and end wall 12 which end wall is provided with a slot or opening 13 and a second smaller slot or opening 14 spaced therefrom to provide a pivot or bar portion 15 between the slots 13 and 14.

The other parts of this swivel are formed from a blank 16, shown generally in Fig. 6, which has 25 a pair of arms 17 formed at one end with a slot 18 between them, while its other end is formed thinner as at 19 to be easily rolled into an eye or loop formation. This is also grooved as at 20 in an alignment with the slot 18.

This blank is bent up into a bow form 21, as shown in Fig. 7, with a hook portion 22 which is threaded inwardly through the opening 13 so as to receive the bar 15 within the space 23 of this hook after which the hook is closed about the bar 15, as shown in Fig. 3, so that its end portion 24 is brought snugly against and within the shoulder 25, as shown in Fig. 3, to provide a closed loop about the bar 15 and yet one which is sufficiently loose so that the same may rock 35 about the bar as a pivot. The opposite end of the bow 26 with its arms 17 is then inserted into the bow 28 with its arms 17 is then inserted into the opening 13 with its notch 27 in engagement with the edge 28 of this opening and its arms 17 extending toward the pivot bar 15 so as to substantially close the entrance to the hollow body 10 and prevent the entrance of tumbling shot 40 therein where it is soldered in place.

A spring of generally U-shaped formation and designated 29 is then slipped in place in the 50 slot 18 between the arm 17 with one of its ends 30 engaging the end of the slot 18 and the other of its ends 31 engaging the end of the slot 20 so as to prevent it from being urged outwardly from the body while its bight portion 32 ex- 55

tends into the hollow body 18. The end 31 engages near the end of the slot 20 so as to be outwardly of the pivot.

5 The tongue 33 is then formed by severing the bow along the line 34 at an angle so that the ends 35 and 36 thus formed will provide a stop to prevent the outward swinging movement of the tongue 33 beyond the position shown in Fig. 2, although allowing inward movement to the position shown in Fig. 3, by compression of the spring 10 to permit some loop or other to be inserted into the bow for holding the same in position.

15 The stud portion 37 of the body receives a collar 38 and is headed over as at 39 to provide a shoulder and prevent the escape of the collar, which collar has attached thereto the ring 40 soldered at one end and inserted in the opening 41 at a diametrically opposite location in a usual formation for attaching it to some desired object.

20 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A connector comprising a seamless hollow body provided with an end wall having spaced 30 openings to provide an integral pivot bar, a bow secured to said body, a tongue cooperating with said bow and having a portion embracing said pivot bar to rockably mount the tongue thereon, and a spring within the body and having one

end portion extending outwardly and engaging said tongue outside of said body to swing the tongue toward the bow.

2. A connector comprising a seamless hollow body provided with an end wall having spaced 5 openings to provide an integral pivot bar, one of said openings receiving therethrough a bow which is fixed to the body, a tongue embracing said pivot bar to rockably mount the tongue thereon, and also a spring contacting and acting to 10 relatively urge said bow and tongue in opposite directions.

3. A connector comprising a seamless hollow body provided with an end wall having spaced 15 openings to provide an integral pivot bar, one of said openings receiving therethrough a bow which is fixed to the body, a tongue embracing said pivot bar to rockably mount the tongue thereon, and arms on said bow extending toward said tongue to close said opening to the body through 20 which said bow extends.

4. A connector comprising a seamless hollow body provided with an end wall having spaced 25 openings to provide an integral pivot bar, one of said openings receiving therethrough a bow which is fixed to the body, a tongue embracing said pivot bar to rockably mount the tongue thereon, a spring contacting and acting to relatively urge said bow and tongue in opposite directions, and arms fixed on the bow adjacent the body and located on either side of said spring and extending toward said tongue to close the said opening to the body through which said bow extends.
